(57) **CLAIM**

The ornamental design for a mount for sight, as shown and described.

DESCRIPTION

FIG. 1 is a perspective view of a mount for sight showing my new design;

FIG. 2 is a front view thereof;

FIG. 3 is a rear view thereof, from an end opposite that of FIG. 2;

FIG. 4 is a side view thereof;

FIG. 5 is a side view thereof, from a side opposite that of FIG. 4;

FIG. 6 is a top view thereof; and,

FIG. 7 is a bottom view thereof.

The broken lines in the drawings depict unclaimed portions of the mount for sight only and form no part of the claimed design.
